CLAIM

(30) **Foreign Application Priority Data**

The ornamental design for expansion valve, as shown and described.

Sep. 27, 2007 (JP) D2007-026213

DESCRIPTION

(51) **LOC (9) Cl.** **23-01**

FIG. 1 is a right front perspective view of an expansion valve;

(52) **U.S. Cl.** **D23/233**

FIG. 2 is a left rear perspective view thereof;

(58) **Field of Classification Search** D23/233–237,
D23/244–249; 137/625.48; 251/14, 64;
62/222–225, 197, 115, 527, 210; 236/63–64,
236/66, 92 B; 285/189, 208, 211, 368

FIG. 3 is a front view thereof;

See application file for complete search history.

FIG. 4 is a rear view thereof;

(56) **References Cited**

FIG. 5 is a plan view thereof;

U.S. PATENT DOCUMENTS

FIG. 6 is a bottom view thereof;

D427,285 S * 6/2000 Watanabe D23/233

FIG. 7 is a left side view thereof; and,

FIG. 8 is a right side view thereof.
